Fig. 13.

A technical line drawing of a mechanical assembly, likely a valve or fitting. It features a central vertical stem with a handle at the top. A horizontal rod extends from the side, supported by a lever system. Two callout lines point to specific parts: line 68 points to a small circular component near the base of the stem, and line 69 points to a larger rectangular component further up the stem. The drawing is labeled 'Fig. 14.' in the bottom right corner.

UNITED STATES PATENT OFFICE.

LAWRENCE W. DAUGHENBAUGH, OF ALTOONA, PENNSYLVANIA, ASSIGNOR TO WALTER P. MURPHY, OF CHICAGO, ILLINOIS.

END DOOR FOR RAILWAY-CARS.

1,186,754.

Specification of Letters Patent. Patented June 13, 1916.

Original application filed August 25, 1913, Serial No. 786,453. Divided and this application filed March 27, 1914. Serial No. 827,687.

To all whom it may concern:

Be it known that I, LAWRENCE W. DAUGHENBAUGH, a citizen of the United States, residing at Altoona, in the county of Blair and State of Pennsylvania, have invented certain new and useful Improvements in End Doors for Railway-Cars, of which the following is a specification.

My invention relates to doors of metal construction and has for one of its primary objects to provide a metal door structure, that is, a door and its frame, suitable for the end of a railway box car, particularly a sheet metal car end, which will be strong, durable, inexpensive to manufacture and waterproof, and which for these and other reasons may be advantageously employed in this or analogous situations.

A further object of the invention is to provide in a door construction for sheet metal car ends, a door frame or supporting and guiding means for the sliding door which is so constructed that it will not be distorted so as to prevent the door from being opened or closed, or so as to make the movements of the door difficult, in case the sheet metal structure to which it is attached becomes bent or deflected, for example, by the interior thrusts and pressures of the cargo.

The invention consists of the several devices, arrangements and combinations hereinafter described and claimed for carrying out the above stated objects.

The invention is illustrated, in a preferred embodiment, in the accompanying drawings wherein—

Figure 1 is a fragmentary view, in elevation, of a corrugated sheet metal car end having an opening fitted with the door structure of my invention, the door being in closed position; Fig. 2, a sectional plan taken on line 2—2 of Fig. 1; Fig. 3, a vertical section on line 3—3 of Fig. 1; Fig. 4, a view showing the door and frame in elevation, with the door in its open position; Fig. 5, a perspective view of the door frame element which supports and provides a guideway for the lower edge of the door; Fig. 6, a view, in perspective, of the bracket for supporting the end of the element shown in Fig. 5; Figs. 7 and 8, perspective views of the clips for receiving and engaging the door when in open position; Fig. 9, a view,

in elevation, of a modified construction in which the door is corrugated; Figs. 10 and 11, sectional views taken respectively on lines 10—10 and 11—11 of Fig. 9; Fig. 12, a view similar to Fig. 1 showing the preferred construction of the door applied to a corrugated sheet metal car end in which the corrugations terminate a short distance from the edge of the door opening; Figs. 13 and 14, enlarged sectional views taken on lines 13—13 and 14—14, respectively, of Fig. 12; Fig. 15, a perspective view of the guide member for the upper edge of the door, and Fig. 16, a view, in perspective, of a channel-shaped member which fits over the forward edge of the door shown in Figs. 12 to 14, 70 inclusive.

Like characters of reference designate like parts in the several figures of the drawings.

Referring first to Figs. 1 to 8 inclusive, 25 designates a sheet metal car end, for example, a sheet metal car end, which is shown as formed with pressed stiffening ribs or corrugations 26 and with a door opening 27. Arranged in the door opening 27 is a, preferably cast, door frame 28 provided with a flange 29 overlapping the portions of the end sheet adjacent the door opening and secured thereto by rivets 30. As, in the construction shown, the door opening interrupts the corrugations 26, the flange 29 of the door frame is fluted or corrugated so as to closely fit the structure to which it is attached. The upper member of the door frame is formed with a channel-shaped web 31 providing a guideway for the upper edge of the door 32. Preferably the web 31 is carried continuously around one end or forward side of the door frame, as indicated at 33, so as to provide a recess for the forward edge of the door. The guideway for the lower edge of the door is provided with a strip 34 (Fig. 5) secured to the lower member of the door frame by rivets 35 and formed with a channel-shaped part 36, the channel 37 of which is preferably open at opposite ends. Preferably the element 34 is longer than the width of the door so that it supports the door when in open position, the rearwardly projecting part of the element being supported by a bracket 38 (Fig. 6) secured to the end sheet 25.

The door 32 slides in the guideways 31,

36 and is preferably formed of sheet metal and provided with a handle 39. The rear edge of the door is bent over so as to provide a U-shaped part 40 which is adapted to 5 fit over an outturned flange 41 cast on the door frame.

42 (Fig. 7) designates an angular stop member which is secured to the end sheet 25 so that the rear edge of the door bears 10 against it when the door is in its open position. Preferably a clip 43 (Fig. 8) is provided having a channel-shaped part 44 adapted to receive the upper edge of the door when opened. The door is therefore 15 firmly supported and held in its open position which is essential in order that it should not be distorted or otherwise injured by the vibration of the car when in motion. It often happens that through carelessness the 20 end door of a railway car is left open, while the train is in motion.

The door frame is preferably provided with a pivoted gravity latch 45 adapted to engage in a recess 46 formed in the door, 25 when the door is closed, and also to stand in front of the forward edge of the door when the latter is open. The latch and the parts operatively associated therewith are not claimed herein as they form the subject matter of my pending application Serial No. 786,453, filed August 25, 1913, of which the present application is a division.

In the construction above described, the interlocked engagement of the door, when 35 closed, with the door frame, will, under ordinary circumstances, effectively prevent water from getting into the car through the door structure. However, in order to make this perfectly certain I preferably form the 40 lower member of the door frame with one or more drainage channels 47 which open into the channel 37 in which the lower edge of the door slides so that if by any chance water should get in between the door and 45 the door frame it will be intercepted by these channels and drained out.

The construction shown in Figs. 9 to 11 inclusive is essentially the same as that just described except that the door 32^a is formed 50 with a plurality of pressed out ribs or corrugations 32^b which preferably run vertically of the door. This construction makes it advisable to employ a different form of locking device, which is shown as consisting of 55 a pivoted latch 45^a, but will not be particularly described as, under the requirement for division of the parent application above referred to, the locking means forms a separate invention from the door construction *per se*.

60 It will be seen that with a door frame constructed as above described the end sheet is not materially weakened by cutting the door opening in it since any stresses on the corrugations 26 on one side of the door opening 65 are taken up by the door frame and trans-

mitted to the corrugations on the other side. By forming the door with corrugations, as shown in Figs. 9 to 11 inclusive, the door will be made very stiff and strong. The flange 29 on the door frame preferably lies 70 back of the edge of the end sheet so that there is little or no likelihood that water will work into the car at this place.

In the preferred construction shown in Figs. 12 to 16 inclusive, 50 designates a sheet 75 metal car end having a door opening 51 cut therein and formed with corrugations 52, which terminate a short distance from the edge of the door opening so as to provide a flat surface 53 adjacent thereto. The door 80 frame 54 is preferably a malleable iron casting and is arranged within the opening so that the flange 55 may be secured to the inner face of the flat surface 53 by means of rivets 56. The door 57 is supported in the 85 channel-shaped portion 58 of a guide strip 59, similar to the one shown in Fig. 5, and which is secured to the lower member of the door frame by rivets 60. Secured to the forward side of the door frame is a channel 90 shaped member 61, the channel portion 62 of which fits over the forward edge of the door when the latter is in closed position. The channel portion 62 is formed at its lower end with an extension 63 which closes 95 the opening in the forward end of the lower guideway 58, and at its upper end fits with an enlarged portion 64 of the upper guideway 65 which is secured to the upper member 100 of the door frame by rivets 66. By having the guideways overlapped in this manner water is prevented from entering the car around the forward edge of the door. In order to prevent any water from working into the car between the guideway 65 and the upper 105 member of the door frame, I have provided the attaching flange 67 of the guideway 65 with a downwardly extending flange 68 which projects into a channel 69 formed in the upper member of the door frame. The rear edge of the door is bent over 110 so as to provide a U-shaped part 70 which is adapted to fit over an outturned flange 71 cast on the door frame and thereby prevents 115 water from entering the car at this point.

In addition to providing the door with a corrugation 72 which forms a recess into which the gravity lock drops when the door is in closed position, as described in my co-pending application above referred to, I 120 preferably form the door with a similar corrugation 73 which provides a recess adapted to serve the purpose of a handle when it is desired to manipulate the door from the inside of the car.

125 My invention, it will be seen, provides a door structure, the operativeness of which is not affected by the possible bending or deflection of the wall to which it is fitted. The end of a railway box car is subjected to very 130

heavy thrusts and pressures due to the shifting of the cargo when the car stops and starts. These inertia thrusts are likely to cause a deflection of the end wall, either 5 permanent or temporary, which might prevent the manipulation of the door in case the guides for the latter were connected directly to the sheet metal constituting the car end. My construction provides a rigid door 10 frame, preferably a malleable casting, which surrounds the door opening and to which the door guides are rigidly secured. If the sheet metal of the car end becomes permanently bent or is temporarily deflected, the 15 distortion does not throw the door guides out of alinement with each other. The door structure as a whole may shift its angular position but this will not prevent the door from being opened and closed since the relative position of the parts of the door and its 20 guides is not changed.

While I have described my invention in certain preferred embodiments, it will be understood that modifications might be 25 made without departure from the invention so that I do not wish to be understood as limiting the invention to the precise constructions, arrangements and devices shown.

I claim:

- 30 1. The combination with the framing of a box car of a sheet metal wall panel secured at its edges only to said framing and thin enough to be flexible under ordinary service conditions having a door opening therein 35 which does not extend to said edges, a rigid door frame attached to said panel around said opening, means providing door guides on said frame, and a sliding door mounted in said guide.
- 40 2. The combination with the framing of a box car, of a sheet metal wall panel which is thin enough to be flexible under ordinary service conditions and has a door opening therein, a door frame casting comprising a 45 flange secured flatwise to the inner side of said panel and an outwardly projecting rectangular member, a slidable door and means providing guides for the door comprising a channeled guide strip secured to one side of

said rectangular member with one end projecting beyond the door opening. 50

3. The combination with the framing of a box car, of a sheet metal wall panel which is thin enough to be flexible under ordinary service conditions and has a door opening 55 therein, a door frame casting comprising a flange secured flatwise to the inner side of said panel and an outwardly projecting rectangular member, a slidable door, oppositely disposed channeled guide strips secured to said rectangular member between which the door is supported and a stop strip secured to said rectangular member and channeled to receive the forward edge of the door. 60

4. The combination with the framing of a box car, of a sheet metal wall panel which is thin enough to be flexible under ordinary service conditions and has a door opening therein, a door frame casting comprising a 70 flange secured flatwise to the inner side of said panel and an outwardly projecting rectangular member, a slidable door, oppositely disposed channeled guide strips secured to said rectangular member between which the 75 door is supported, and a stop strip secured to said rectangular member and channeled to receive the forward edge of the door, said strips formed so that each strip closes the end of the channel in the adjacent strip. 80

5. The combination with the framing of a box car, of a sheet metal wall panel which is thin enough to be flexible under ordinary service conditions and has a door opening therein, a door frame casting comprising a 85 flange secured flatwise to the inner side of the panel and an outwardly projecting rectangular member formed adjacent said flange with a depression providing a transverse channel, a slidable door and guiding 90 means for the door comprising a guide strip on the upper side of the rectangular member the inner edge of which projects over said channel.
